ABSTRACT OF THE DISCLOSURE

Apparatus centering and spreading a ball of plastic clay on a rotating potter's wheel, including an elongated arm hinged for pivotal movement about vertical and longitudinal axes above and overlying the potter's wheel, having a downwardly facing sponge therein for engaging the clay and pressing it downwardly, and a panel guided for vertical movement on the arm to rest on the surface of the potter's wheel and laterally engage the ball of clay. A retractable cavity forming member and a retractable support for the free end of the arm are also mounted on the arm.

BACKGROUND AND OBJECTS OF THE INVENTION

The present invention relates to apparatus for centering and spreading a plastic ball of clay on a potter's wheel so as to enable the beginner or learner to exactly center and spread to the proper depth the starting ball of clay.

The initial steps of centering the starting plastic ball of clay on a potter's wheel in connection with the production of a pot and spreading the clay to a proper depth requires considerable skill and has been a source of great difficulty to beginners. Before anything is created on the potter's wheel, the ball of plastic clay must first be truly centered while the potter's wheel is revolving and then must be spread to a depth such that when the clay is cut from the wheel with a fine wire after forming the pot, a bottom of the desired thickness will be left on the pot. This proper centering and spreading of the clay requires many hours of tedious practice for the beginner.

An object of the present invention, therefore, is the provision of novel apparatus associated with a potter's wheel to facilitate the initial centering of the plastic ball of clay on the potter's wheel and spreading of the clay to the proper depth.

Another object of the present invention is the provision of apparatus as described in the immediately preceding paragraph, which is exceedingly simple and inexpensive in construction and may be readily applied to existing potter's wheel structures with a minimum of expense.

Yet another object of the present invention is the provision of a novel apparatus for attachment to potter's wheels to facilitate initial centering and spreading of the plastic ball of clay on the potter's wheel, particularly to enable beginners and students to readily perform these initial procedures, and which can be readily moved out of the way or placed aside so as not to interfere with use of the potter's wheel when the operator becomes more skilled.

Other objects, advantages and capabilities of the present invention will become apparent from the following detailed description, taken in conjunction with the accompanying drawings illustrating a preferred embodiment of the invention.

BRIEF DESCRIPTION OF THE FIGURES

FIG. 1 is a perspective view showing fragmentary portions of a potter's wheel and the clay centering and spreading apparatus of the present invention applied thereto;

2

FIG. 2 is a vertical transverse section view of the upper portions of a potter's wheel and the clay centering and spreading apparatus, taken along the line 2—2 of FIG. 1;

5 FIG. 3 is a fragmentary top plan view taken along the line 3—3 of FIG. 2;

10 FIG. 4 is a vertical section view of the apparatus, taken along the line 4—4 of FIG. 2, illustrating the operation of the apparatus in centering the ball of plastic clay;

15 FIG. 5 is a side elevation view illustrating the apparatus in lowered position after the ball of clay is centered and in condition to spread the clay so as to form an upwardly opening center cavity of appropriate depth, part of the clay ball being broken away to illustrate the cavity-forming portion of the apparatus, and

20 FIG. 6 is a vertical section view taken along the line 6—6 of FIG. 5.

DETAILED DESCRIPTION OF THE INVENTION

25 Referring to the drawings, wherein like reference characters designate corresponding parts throughout the several figures, there is illustrated a potter's wheel apparatus, generally indicated by the reference character 10, comprising a frame 11 of conventional construction having vertical and horizontal support members in the illustrated embodiment, all arranged to provide a generally rectangular well 12 in which is located the rotatable potter's wheel 13. The potter's wheel 13 may be supported in any conventional manner, for example by means of a vertical depending shaft 14, extending through and rotatably supported in a support sleeve 15 and having a pulley 16 keyed to the lower end thereof. In the illustrated embodiment, a belt 17 is trained about the pulley 16 and 30 a pulley 18 on a reduction pulley unit 19, suitably journaled on the frame 11, another pulley 20 of the reduction unit 19 having a belt 21 trained thereabout and about a pulley 22 on the output shaft of an electric drive motor 23 suitably mounted on the frame, all providing 35 a drive source for the potter's wheel 13.

40 The novel clay centering and spreading apparatus of the present invention is indicated generally by the reference character 25 and, in the embodiment herein illustrated, is of extremely simple construction made from 45 readily available lumber and hardware components. In the herein illustrated embodiment, the apparatus 25 comprises an elongated arm 26, for example a board about two to three feet long of approximately two inch by four inch cross section timber coupled at one end by bolt 27 to hinge plate 28 of hinge 29, having another hinge plate 30 fixed to a vertical supporting board 31 secured to the frame. The hinge plate 30 is affixed to the support post 31 so that the hinge axis is disposed horizontally while the bolt 27 is disposed vertically, thus providing a substantially universal hinge axis for the arm 26 so that it 50 can be moved about either vertical or horizontal axes. A sponge 32, for example a rectangular sponge approximately two inches thick, four inches wide and six to eight inches long, secured to a rectangular, rigid base member 33, formed for example from a board of similar material to the arm 26, is affixed to the underside of the arm 26 in depending relation centered over the potter's wheel 13. To the right-hand side of this sponge 32, as viewed in FIG. 1, is a floating centering board 34, 55 which may be approximately ten inches by twelve inches and of any desired thickness supported for free floating, vertical movement in laterally flanking guide members 35, fixed to the side of the arm 26 adjacent the location of the sponge 32.

60 A dowel supporting board 36, formed for example from one inch by eight inch lumber, is disposed in a horizontal position across the front of the frame 11 adjacent the

place where the potter stands and located in plane approximately three inches above the plane of the potter's wheel 13. In the center region of the dowel supporting board 36 are a plurality of dowel holes 37 spaced approximately one inch apart laterally and adapted to removably receive dowel pin 38. The dowel holes 37 are so located relative to the line from the bolt 27 to the center axis of the potter's wheel 13 to so locate the arm 26 when it abuts the dowel pin 38, and thus locate the floating centering board 34 relative to the axis of the potter's wheel 13, to provide a centering wall spaced relative to the potter's wheel axis to shape the clay ball, indicated by reference character 39, into cylinders of selected diameters.

In order to support the arm 26 against downward movement from a selected position disposing the bottom of the sponge 32 at a selected height above the potter's wheel 13, a hinge 40, of the gate hinge type having one elongated hinge plate 41, which is considerably longer than the other hinge plate 42, is secured to the outer end of the arm 26 by screws or fastening means extending through the smaller hinge plate 42. The hinge axis is located immediately outwardly of the end of the arm 26 so that the longer hinge plate 41 may be turned downwardly and its lower end rested against the dowel supporting board 36.

A hinge 43, also of the gate hinge type construction, is affixed at its smaller hinge plate 44 to the top of the arm 26 at a position to overlie the center of the potter's wheel, with its hinge axis paralleling and registering with the left edge of the arm 26, as viewed in FIG. 1, so that the longer hinge plate 45 may be turned downwardly into a vertical depending position. The longer hinge plate 45 is of generally triangular configuration, converging to a tip at its free end, and has a small sponge 46 on its free end to engage the clay and spread the same to form an upwardly opening cavity in the center of the clay ball, as will be later described.

In the operation of this apparatus by the student, the student should mix thoroughly about one or two pounds of plastic clay and make it into a round ball, and then place this ball on the center of the potter's wheel 13 while the wheel is dry. The sponge 32 is then moistened, the dowel pin 38 is inserted into the appropriate dowel hole 37 for the desired diameter of the centered starting ball of clay, and the arm 26 is lowered to bring the sponge 32 into contact with the top of the clay. The floating board 34 is placed in the guide members 35 and lowered until its bottom contacts the upper surface of the potter's wheel 13. The operator then presses down firmly on the free end of the arm 26, exerting pressure from the moistened sponge 32 on the top of the clay ball 39 while the potter's wheel 13 is revolved. This is continued until the clay is forced to a cylindrical configuration with its cylindrical surface engaging the board 34 which, since the board forms a tangent of a circle about the axis of the potter's wheel 13 of the proper diameter, restricts the lateral extent to which the clay 39 can be spread. The dowel pin 38 is then removed, the floating board 34 is removed, the longer hinge plates 41 and 45 of the hinges 40 and 43 are dropped to vertical depending position and the arm 36 is pressed downwardly with the hinge plate 45 approximately centered over the potter's wheel 13 to spread the clay ball 39 out from the center thereof and form the cavity 47, illustrated in FIG. 5 therein, having a depth such that its bottom is spaced appropriately from the top of the potter's wheel 13 by engagement of the longer hinge plate 41 with the dowel supporting board 36. Then, with the potter's wheel 13 still revolving, the arm 26 can be swung upwardly and out of the way and the clay may be shaped free-hand to the desired final configuration for the pot. In accordance with usual procedure, when the pot is completely shaped, the potter then cuts through the lowermost portion of the clay immediately adjacent the upper surface of the potter's wheel 13 by the usual fine wire, leaving a bottom on the pot of appropriate

thickness because of the action of the hinge plate 41 in limiting the depth to which the sponge 46 forms the cavity in the clay ball. By this apparatus, the steps of centering and spreading the clay ball, which was formerly very difficult for the beginner when performed by hand, are considerably simplified by these mechanical aids, permitting the beginner to readily perform these initial steps and then proceed with hand-forming or shaping of the desired clay article.

While but one particular embodiment of the present invention has been specifically shown and described, it will be apparent that various modifications may be made therein within the spirit and scope of the invention, and it is desired, therefore, that only such limitations be placed on the invention as are imposed by the prior art and set forth in the appended claims.

I claim:

1. Apparatus for centering and spreading a plastic ball of clay on the upper surface of a rotating potter's wheel, comprising a supporting member spaced laterally from the potter's wheel, an elongated rigid arm hingedly supported at one end to said support member about vertical and horizontal pivot axes for vertical angular movement above the plane of said upper surface and for horizontal angular movement to positions disposing an intermediate portion of the arm vertically overlying said upper surface, a downwardly facing sponge carried by said intermediate portion to bear downwardly upon the ball of clay on the potter's wheel, and a vertical panel member removably supported by said intermediate portion in a vertical plane adjacent said sponge and guided for vertical movement relative to the arm to rest upon said upper surface at various positions spaced from the axis of said upper surface and paralleling a diameter thereof to define a vertical wall to laterally engage the ball of clay and urge the same into a cylindrical configuration during rotation of the potter's wheel.

2. Apparatus as defined in claim 1, wherein said arm includes a free end spaced laterally from the potter's wheel on the opposite side thereof relative to said support member, a platform member disposed alongside a portion of the potter's wheel and underlying said free end having a plurality of dowel sockets therein, and a vertical dowel member removably locatable in said sockets and having a height to reach at least alongside said free end portion to engage and locate the arm at angular positions about the vertical pivot axes appropriate to locate said panel member to form the ball of clay into cylinders of selected diameter.

3. Apparatus as defined in claim 1, wherein said arm includes a free end located on the opposite side of the potter's wheel from the support member, a platform member underlying said free end, and a movable arm support on said free end having an elongated abutment portion positionable in depending relation below said arm for a selected distance to engage said platform and thereby support the arm at a preselected position about its horizontal hinge axis.

4. Apparatus as defined in claim 2, wherein a movable arm support on said free end having an elongated abutment portion positionable in depending relation below said arm for a selected distance to engage said platform and thereby support the arm at a preselected position about its horizontal hinge axis.

5. Apparatus as defined in claim 3, wherein said arm support is a hinge member having a first hinge plate fixed to said arm and a second, elongated hinge plate pivotable about a substantially horizontal hinge axis into downwardly extending relation and having a lower free end spaced a selected distance below said hinge axis and arm to abut said platform and support the arm a predetermined distance above the potter's wheel.

6. Apparatus as defined in claim 4, wherein said arm support is a hinge member having a first hinge plate fixed to said arm and a second, elongated hinge plate pivotable

about a substantially horizontal hinge axis into downwardly extending relation and having a lower free end spaced a selected distance below said hinge axis and arm to abut said platform and support the arm a predetermined distance above the potter's wheel.

7. Apparatus as defined in claim 1, wherein a cavity forming element is carried by the intermediate portion of said arm including an elongated plate portion movable about a substantially horizontal pivot axis relative to said arm to a downwardly extending position disposing its lower free end a selected distance below the arm, said lower free end of said plate portion having a sponge tip to engage the ball of clay and form an upwardly opening cavity therein of a depth determined by the vertical angular position of said arm as the arm is moved downwardly about its horizontal pivot axis to force the sponge tip into the ball of clay.

8. Apparatus as defined in claim 3, wherein a cavity forming element is carried by the intermediate portion of said arm including an elongated plate portion movable about a substantially horizontal pivot axis relative to said arm to a downwardly extending position disposing its lower free end a selected distance below the arm, said lower free end of said plate portion having a sponge tip to engage the ball of clay and form an upwardly opening cavity therein of a depth determined by the vertical angular position of said arm as the arm is moved downwardly about its horizontal pivot axis to force the sponge tip into the ball of clay.

9. Apparatus as defined in claim 4, wherein a cavity 30

forming element is carried by the intermediate portion of said arm including an elongated plate portion movable about a substantially horizontal pivot axis relative to said arm to a downwardly extending position disposing its lower free end a selected distance below the arm, said lower free end of said plate portion having a sponge tip to engage the ball of clay and form an upwardly opening cavity therein of a depth determined by the vertical angular position of said arm as the arm is moved downwardly about its horizontal pivot axis to force the sponge tip into the ball of clay.

10. Apparatus as defined in claim 7, wherein said cavity-forming element is a hinge of the gate hinge type having a first hinge plate secured in substantially horizontal position on said arm, and a second elongated substantially triangular hinge plate coupled to said first hinge plate along a pivot axis paralleling the longitudinal axis of the arm and having a substantially pointed tip carrying said sponge tip.
